UNITED STATES PATENT OFFICE

RODNEY S. CATHCART, OF PALESTINE, TEXAS, ASSIGNOR TO THE AMERICAN COTTON OIL COMPANY, OF ST. LOUIS, MISSOURI.

OIL EXPRESSING BOX PACKAGE SHAPING MACHINE.

SPECIFICATION forming part of Letters Patent No. 320,848, dated June 23, 1885.

Application filed March 23, 1885. (No model.)

To all whom it may concern:

Be it known that I, RODNEY S. CATHCART of Palestine, Texas, have made a new and useful Improvement in Oil Expressing Box Package Shaping Machines, of which the following is a full, clear, and exact description.

In the present machine a series of pairs of feed and pressure rolls is employed. The rolls of the various pairs are variously spaced apart. Those of the first pair, where the package to be shaped is entered, are spaced the farthest apart, those of the next pair not so far apart, and those of the next pair are still nearer together, and so on through-out the series, through which the package is passed, and by means of which series what may be termed a "progressive pressure" is imparted to the package as well as a form suitable to the oil-expressing box for which it is intended.

The annexed drawings, making a part of this specification, exhibit the most desirable mode of carrying out the improvement.

Figure 1 is a side elevation of the machine. Fig. 2 is a plan. Fig. 3 is a horizontal section on the line 3 3 of Fig. 1. Fig. 4 is a vertical longitudinal section upon an enlarged scale on the line 4 4 of Fig. 2; and Fig. 5 is a vertical transverse section on the line 5 5 of Fig. 2.

The same letters of reference denote the same parts.

The series may consist of any suitable number. Three pairs of rolls are generally sufficient, and but three are shown in the drawings. A A' represent the first pair, B B' represent the second pair, and C C' represent the third pair. The rolls of the first two pairs are preferably fluted, and (as shown in plan and side view) are preferably convex. Of the last pair the rolls are straight; the upper one, C, is smooth, and the lower one, C', slightly fluted. The rolls are arranged transversely in the machine, which also is provided with mechanism for driving the rolls, and also with two tables, one, D, of which supports the package as it is entered between the first pair of rolls, and the other, E, receives the package from the last pair of rolls. The lower rolls, A' B' C', are journaled in fixed bearings a' b' c', and so as to bring the tops of those rolls at a level, or thereabout, with the tables D E. The bearings a b c of the upper rolls, A B C, are vertically adjustable in the uprights F F,

with which the frame of the machine is provided, and they, by means of the nuts G, are adapted to be held at different levels, as shown. The springs H provide for a certain amount of elasticity in the bearings, so that the upper rollers can yield in an upward direction when an undue pressure is upon them.

Power is imparted to the machine by means of the pulley I, Fig. 2, which is attached to the shaft J. The sprocket-wheel K is attached to the shaft J. The sprocket-wheel L is attached to the shaft M. The shaft of the rolls A B C A' B' C' are each provided with a sprocket-wheel, N. By means of the chain belt O, which passes around all of the sprocket-wheels K L N, as represented in Fig. 1, the motion of the pulley I and shaft J is communicated to the rolls A A', B B', C C'. The material—cotton seed, for instance—is generally inclosed in a woolen bag, and before being passed through the machine the package is more or less rounded in form.

The rolls A A' operate both to feed the package into the machine and to partially flatten it. The rolls B B' feed the package farther along and further flatten it, and by means of the rolls C C' the shaping of the package into a square bundle of uniform thickness of the proper dimensions for the oil-expressing box is completed and the package delivered onto the table E.

I claim—

1. An oil expressing box package shaping machine, having a series of pairs of rolls, the rolls of the various pairs being variously spaced apart, substantially as and for the purpose described.

2. The combination of the rolls A A', B B', C C', relatively arranged as shown and described, and the tables D E, substantially as set forth.

3. The combination of the fluted convex rolls A A', the fluted convex rolls B B', and the straight rolls C C', substantially as described.

4. The combination of the tables D E, the rolls A A', B B', C C', relatively arranged as described, the shafts J M, the sprocket-wheels K L N, and the chain-belt O, substantially as described.
